Primary Examiner — Cathron Brooks*Assistant Examiner* — Sydney R Buffalow(74) Attorney, Agent, or Firm — Abelman, Frayne & Schwab(57) CLAIM

The ornamental design for children's cutlery, as shown and described.

DESCRIPTION

FIG. 1 is a top, front and left side perspective view of children's cutlery showing the new design;

FIG. 2 is a top plan thereof;

FIG. 3 is a front elevation thereof;

FIG. 4 is a right side elevation thereof, the left side elevation being a mirror image thereof;

FIG. 5 is a rear elevation thereof; and,

FIG. 6 is a bottom plan thereof.

The broken lines illustrate portions of the children's cutlery and form no part of the claimed design.

1 Claim, 3 Drawing Sheets*FIG. 3*
